UNITED STATES PATENT OFFICE.

JOHN A. CRAWFORD, OF ALLEGHENY, PENNSYLVANIA.

SMOKE-CONSUMER.

SPECIFICATION forming part of Letters Patent No. 586,477, dated July 13, 1897.

Application filed April 24, 1897. Serial No. 633,565. (No model.)

To all whom it may concern:

Be it known that I, JOHN A. CRAWFORD, a citizen of the United States, residing at Allegheny, in the county of Allegheny and State of Pennsylvania, have invented certain new and useful Improvements in Means for Consuming Smoke; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to smoke-consumers for steam-boiler and other furnaces, and is an improvement on Letters Patent granted to me, No. 540,780, bearing date June 11, 1895; and the object of the invention is to take partially-heated air from the ash-pit and more intensely-heated air from a casing in the bridge-wall, said casing also taking the partially-heated air from the ash-pit, no outside or cold air being inducted into the casing in 20 the bridge-wall or in the pipes, except from the ash-pit, said partially-heated or super-heated air, as the case may be, is taken through pipes, preferably crooked pipes, by a steam-jet at a suitable point, inducting above the 25 grate-bars at the lower edge of the fire (in the fire-box) the gases or fire, as it may be, and distributing the same above the coal or on top of the coal, at the point of combustion igniting instantly thus preventing smoke entirely by instantaneous combustion.

The invention consists in the combination and arrangement of the several parts, as will be hereinafter more in detail described, and particularly pointed out in the claims.

40 In the accompanying drawings, to which reference is had and which fully illustrate my invention, Figure 1 is a front elevation, partly broken away, to show the flues or pipes in front of the furnace. Fig. 2 is a cross-section of the same, showing vertical flues or pipes in the side walls of the furnace. Fig. 3 is a longitudinal vertical section. Fig. 4 is a longitudinal horizontal section cut through the flues for superheating the air. Fig. 5 is 45 an enlarged sectional view of one of the pipes on side of furnace for conducting the air and gas to the point of combustion. Fig. 5^a is a

detail of valve on bottom of pipe. Fig. 6 is a similar view of the pipes used in front of the furnace. Fig. 7 is a detail of one of the 55 short pipes used when an obstruction is met. Fig. 8 is an enlarged sectional view of the valve for controlling steam-jets. Fig. 9 is an enlarged detail section of the iron casing through bridge-wall, showing valve for controlling hot-air flues.

A designates the front wall of the furnace, and B the side walls of the same.

C designates the face-plate, secured to the front wall of the furnace.

D designates a pipe or flue formed in the bridge-wall and extending nearly or entirely around the furnace-chamber.

E designates the fire-doors, and F F those of the ash-pit, formed, respectively, in the 70 front wall and face-plate of the furnace.

G designates a steam-pipe connected with a steam-dome H by means of the right-angular branch pipe I, having a branch pipe G' running across the front of the furnace and supplying steam to the steam-jets in front of the furnace.

The two branch pipes G² are for supplying steam to steam-jets in side flues of the furnace.

J designates a boiler having connected to its upper portion a smoke-stack J'. This boiler is fitted in a semicircular opening formed longitudinally in a baffle-wall in the interior of the furnace.

K designates hot-air pipes arranged vertically in the flues. In the front wall of the furnace, intersecting at the top and arranged transversely thereto in a slightly-angular position, is a short pipe K², its downward end 90 being directed within the furnace, this pipe being also shown detached in Fig. 7 of the drawings. The opposite end of the pipe K is turned or curved, forming a short pipe K³, and is directed inwardly to the ash-pit directly below the grate-bars L, as shown more clearly in Fig. 6 of the drawings. Near the lower end of the pipe K and formed thereon is another short pipe K⁴, arranged at right angles to K and directed in the same direction as pipe K², the object of this pipe being to conduct the gases in the heated air upwardly in the pipe K, where they are mixed and commingled with the steam in the angular

short pipe K^2 , heretofore described. This pipe K is provided with an opening k , which leads to a casing or chamber D , surrounding or nearly surrounding the fire-chamber, which receives the superheated air from the channel D in the bridge-wall M , as desired.

N designates one or more needle-valves which are applied to the short angular steam-pipes K^2 , by which the steam, air, and gases are forced and controlled in said pipes, any number of the needle-valves or steam-jets being used to suit circumstances.

O designates hot-air pipes used for a similar purpose as those located in the front wall of the furnace, these pipes being somewhat longer and located in the side walls of said furnace. These latter pipes have their upper ends turned to form short pipes o , and are arranged slightly angular in respect to the pipes O , and are directed inwardly into the furnace-chamber, as clearly shown in Fig. 2 of the drawings. Intersecting these pipes and forming a part thereof are short pipes O' , which are arranged at right angles to the pipes O , these pipes O' having for their object to take in the gases which are mixed with the hot air drawn from the ash-pit upwardly through the hot-air pipes O , where it is thoroughly mixed with the hot air and steam before passing out of the short angular extension-pipe o of the hot-air pipe O . Located in the lower end of the pipe O is a valve P , and projected centrally through the same is another needle-valve P' , the former being controlled and operated by a rod p and the latter by a rod p' , the valve P regulating the partially-heated air from the ash-pit and the valve P' regulating the steam where they are mixed in the ascent through the hot-air pipes O and into the furnace-chamber.

In the pipe or flue D , located in the bridge-wall of the furnace, is a steam-jet Q , which, in dotted lines in Fig. 4, is connected to the steam-pipe by a branch pipe Q' to the steam-pipe G' ; also, in this pipe or flue D is located a balance-valve R for closing the superheating-chamber when it is desired to take the partially-heated air directly from the ash-pit, a short channel d connecting the pipe or flue D with the ash-pit.

The operation is as follows: When the furnace is started, the partially-heated air is drawn from the ash-pit and the gas, &c., from above the fire-chamber, and by means of the steam-jets causing a suction, thus drawing the air and gas through the flues and discharging them above the fire-box after being thoroughly mixed, thereby insuring perfect combustion. In the flues in the front wall the steam draws the partially-heated air from the ash-pit and the gases and fire, as it were, from immediately above the grate-bars and distributes it on top of the coal at the point

of combustion. When it is desired to use superheated air instead of using partially-heated air directly from the ash-pit, the air-valves P on the vertical flues or pipes are closed and the valve on the steam-jet Q is turned on, thus forcing open the balance-valve R and drawing the air from the ash-pit through the channel d into the superheating-pipe D in the bridge-wall M around the sides and front of the furnace, where it is drawn into the openings k and o' in the vertical flues or pipes K and O and mixed with the gas in the fire-chamber, where combustion is immediately created, and the smoke is thus entirely consumed.

Having thus described my invention, what I claim as new, and desire to secure by Letters Patent, is—

1. In a steam-boiler furnace, the combination with the walls of the furnace, the ash-pit, the fire-chamber, grate-bars, baffle-walls and boiler thereof, of a series of flues or channels formed upon the inside of the fire-front in the front or long wall; hot-air pipes located in the air-chamber in the front wall and having branch pipes at the upper and near the lower end of the hot-air pipes, the lower branches being located above the grate-bars, and adjustable needle-valves or steam-jets located in the upper end of the hot-air pipes, said jets siphoning the air and gases through to the point of combustion, substantially as set forth.

2. In a steam-boiler furnace, the combination with the front and side walls having flues or channels therein of hot-air pipes located in said channels of the side walls and having the upper inclined branch and the lower right-angular branch pipes projecting therefrom, adjustable needle and oscillating valves located in the bottom thereof and rods projecting therefrom through the ash-pit whereby the heated air and gases are controlled in their ascent through the hot-air front and side wall pipes, substantially as described.

3. In a steam-boiler furnace, the combination with the front and side wall pipes and their valves, of the bridge-wall pipe and its adjustable needle valve or jet, and valve situated in the continuous casing around the fire-chamber, supplying heated air, and steam connecting-pipes located across the front of the furnace and vertical and horizontal portions of the same connecting with the dome of the boiler, substantially as described.

In testimony whereof I affix my signature in presence of two witnesses.

JOHN A. CRAWFORD.
